ALBERT E. GREENE, OF MEDINA, WASHINGTON

ELECTRIC FURNACE

Application filed February 8, 1927. Serial No. 168,676.

My present invention relates to electric arc furnace apparatus and especially to the construction of the mechanical parts of the furnace proper and to the electrode mechanism and the electrode contact details.

My present application is a continuation in part of my applications Serial Numbers, 279,776 filed Feb. 28, 1919, and 623,036 filed March 3, 1923.

10 In my applications of which the present is a continuation in part, I showed certain electrode holder improvements. These included the structure of the electrode contacts in which a watercooled contact is provided with 15 an upper lug with holes in it and copper conductor cables brazed or welded into these holes. This construction provides a means for carrying the current in a cable direct to the contact lug without the necessity of bolted 20 joints along the electrode holder arm. It also provides for a welded or brazed joint on the contact member so that the heat will not affect this connection. The construction provides for carrying the cables along the electrode holder arm and for mounting them on 25 the arm or on the trolley member which carries the arm, using insulating clamps for this purpose.

30 In the building of these electrode holder parts I have also made further improvements over those in my early application. I have provided a special construction of trolley side which serves to hold and support the arm proper, the latter, consisting preferably of 35 a pipe, being bolted between the trolley sides. This construction allows for the movement of the arm as claimed in my earlier application and for the use of the eccentrically mounted rollers to adjust the trolley and arm positions.

40 I have made an improved arm end member which is provided with a laterally extending slot, that is a slot at right angles to the axis of the arm, this slot being placed in the top of 45 the arm end member and I have provided another such slot in the front vertical plane surface of this same member. These slots permit the insulated bolts to pass thru them, and also permit an adjustment of the clamp member laterally with respect to the arm end mem-

ber. This improved construction provides means for adjusting the position of the electrode axis to one side or the other of the arm axis and is a modified form of my invention claimed in my earlier applications. This arm end member is provided with portions which slide over the end of the pipe arm and which have bolts for clamping the arm end member in adjusted position.

These above features and others will now 60 be described with regard to the annexed drawings.

In the drawings, Fig. 1 is an elevation view 65 of an improved electrode holder mechanism and contact embodying my invention.

Fig. 2 is a plan view of the apparatus of Fig. 1.

Fig. 3 is a plan view of the arm end shown in Fig. 1, and embodying my invention.

Fig. 4 is a sectional elevation view of the 70 improved electrode contact shown in Fig. 1 and embodying my invention.

In the drawings, I have shown a trolley which operates on a vertical mast member 1, which may be an I-beam for example. The 75 trolley comprises a main side plate member indicated at 2 on one side of the mast and another side member 3 on the opposite side. These may be cast in one piece or bolted together. Rollers are provided and operate on 80 shafts shown at 4, 5, 6 and 7, the rollers being shown at 8 and 9 in the plan view of Fig. 2. These rollers have flanges as shown and the rollers may be mounted with washers between them and the side plate on one side in 85 order to adjust the position of the roller on the axis of the shaft. Also the shafts may be eccentrically mounted so that the roller axes are eccentric of the shaft pins extending thru the trolley sides, in accordance with 90 the invention of my earlier application.

The trolley sides have extensions indicated at 10 and 11 which serve to hold a pipe arm 12 between them, and bolts serve to hold the sides 10 and 11 together. These bolts are indicated at 13, 14, 15 and 16. A cable is clamped around bolt 15 and serves to raise and lower the electrode holder along the mast. The pipe arm 12 is held at one end in the trolley side members and at the other 100

end holds an arm end member 17 which is clamped around the pipe arm in the same manner as indicated at 10 by bolts like that at 18.

- 5 The arm end member 17 slips over the pipe 12 and may be adjusted in its position into or out from the mast and held in adjusted position. This arm end member is provided with a slot in its top flat surface indicated 10 at 19 and another slot in its vertical flat front surface indicated at 20. Thru these two slots go the insulated bolts 21 and 22 which hold the clamp member 23 against the insulating plates between it and the arm end. 15 These insulating plates, which may be of asbestos wood for example, are shown at 24 and 25. This construction of arm end with the slots provides for adjustment of the clamp to either side of the arm axis so that the 20 position of the electrode may be thus shifted. Likewise the angle of the electrode with the vertical may be adjusted by movement of the arm-end around the pipe.
- 25 The clamp member 23 and the hinge member 23^a serve to hold two contacts, 26 and 27 shown in Fig. 2 against the electrode 29. These contacts are preferably made of cast copper and are shown in section in Fig. 4. 30 The inner contacting surface is shown at 30, and the entrance to the water cooling cavity at 28. Each contact has a lug extending upwardly with two holes which are for the copper cable to enter and be brazed 35 or welded in. These holes are shown at 31 in Fig. 4 and the cables 32 and 33 are shown in place in the lugs in Fig. 1. The bolt 34 serves to hold the clamping members against the contacts. The flexible cables, shown with 40 an insulating covering, are held in place in an insulating member 35 mounted on the trolley side, and cables from the other contact 26 are also provided. The lugs may have more or less holes than the two shown 45 for more or fewer cables.
- The angle of the electrode with the mast may be adjusted by shims under the insulating plates 24 and 25 or by adjustment of the eccentric shafts on the trolley.
- 50 I do not limit myself to the use of single piece masts such as vertical I-beams but may use other constructions, such for example as two channels facing each other and then I may mount the rollers inside the channels 55 engaging the inner front and back surfaces and I may provide the eccentric adjustment of these rollers as described with regard to the rollers of Fig. 1. In such case the upper rollers would engage the front inside surfaces of the opposing channels and the lower rollers would engage the back inner surfaces and I may provide other adjusting rollers inside or outside the channels to adjust the 60 position of the trolley member.
- 65

What I claim is:

1. An electric furnace electrode mechanism comprising an electrode holding arm movable vertically to raise or lower an electrode held thereby, and a clamping member attached to said arm for clamping an electrode, and means for lateral adjustment of the position of said clamping member with respect to the axis of said arm. 70
2. An electrode mechanism comprising a vertically adjustable arm, an arm end member, a clamping member mounted thereon and means for shifting the position of the clamping member horizontally to one side or the other of the horizontal axis of the 80 said arm and for holding the clamping member in the adjusted position. 75
3. An electrode clamping mechanism comprising a clamping member mounted on the end of a horizontal arm but insulated therefrom and having means for lateral adjustment in a horizontal plane to move the axis of a vertical electrode held thereby to the one hand or the other of the axis of the 85 arm. 90
4. In combination, an electric furnace electrode clamping mechanism, comprising an adjustable arm movable vertically, an arm end member having a surface for electrical insulating material to abut, a clamping member held against said insulation, and slotted means for adjusting the position of the clamping member and holding it in such position against the insulation. 95
5. An electrode holding mechanism, comprising a supporting member having an outer flat surface, electrical insulation against said surface and between it and an electrode holding member, insulated bolts holding the two separate members against the electrical 100 insulation and against each other with the insulation between, and slotted holes for adjustment of the position of the electrode holding member serving for adjustment of the electrode axis with respect to the supporting 105 member. 110
6. An electrode holding mechanism comprising an adjustable arm, an arm end member thereon, slotted holes in the surface of said member, an electrode clamping member held against insulation between it and said arm end member and insulated bolts for holding the latter clamping member in adjusted 115 position. 120
7. In an electric furnace, an electrode supporting arm, a clamp supporting member adjustably mounted on said arm adjacent an end thereof, and an electrode clamp adjustably mounted on said clamp supporting member. 125
8. In an electric furnace, an electrode supporting arm, a clamp supporting member adjustably mounted on said arm and movable longitudinally thereof, and an electrode clamp adjustably mounted on said clamp sup- 130

porting member and movable transversely of
the longitudinal axis of said electrode sup-
porting arm.

5 In witness whereof, I have hereunto sub-
scribed my name this 3rd day of January,
A. D. 1927.

ALBERT E. GREENE.
